UNITED STATES PATENT OFFICE.

RUDOLF GOLDSCHMIDT, OF BERLIN, GERMANY.

MEANS FOR WORKING MICROPHONES IN PARALLEL.

1,088,018.

Specification of Letters Patent. Patented Feb. 24, 1914.

Application filed October 1, 1912. Serial No. 723,333.

To all whom it may concern:

Be it known that I, RUDOLF GOLDSCHMIDT, a citizen of Germany, residing at Berlin, Germany, have invented new and Improved 5 Means for Working Microphones in Parallel, of which the following is a specification.

This invention relates to novel means for permitting a plurality of microphones to be effectively worked in parallel, so that when influenced by a common sound wave, the energy required for transmitting the sound more particularly for long distance, is increased accordingly. It was hitherto considered unfeasible to connect microphones in parallel, owing to the fact that it is practically impossible to build not even two microphones which are alike from the start and remain so during prolonged use, as to 10 operate with absolute uniformity. According to my invention this difficulty is effectively overcome by the interpolation of choking coils into the microphone circuits which equalize the differences in current distribution caused by the uneven operation of the microphones.

In the accompanying drawing: Figure 1 is a wiring diagram showing my invention applied to two microphones; Fig. 2 a similar 30 diagram showing the invention applied to three microphones, and Fig. 3 a wiring diagram showing a modified form of the invention applied to three microphones.

Referring to Fig. 1, the letters M_1 and M_2 indicate a pair of microphones which are located at one transmitting station, to be influenced by a common sound wave. Microphones M_1 and M_2 are connected in series with choking coils D_1 , D_2 respectively, the parts M_1 , D_1 and M_2 , D_2 being in turn connected in parallel. Choking coils D_1 , D_2 are relatively so arranged or wound upon a common iron core C that their magnetizing effects produced by the current flowing therethrough have the tendency to become neutralized when equal currents pass therethrough. A considerable choking effect or inductive resistance, however, is obtained, when owing to the differences of the microphones, a compensating current is produced which passes the choking coils in series, the parts M_1 , D_1 , D_2 , M_2 constituting a closed circuit.

If more than two microphones are to be connected in parallel, they may in pairs be rendered uniform in working in manner

analogous to that described with respect to Fig. 1, whereupon the operation of said pairs is rendered uniform by correspondingly coupled choking coils. 60

In Fig. 2 three microphones M_1 , M_2 , M_3 are illustrated which are directly connected to choking coils D_1' , D_2' , D_3' respectively. The latter are in turn connected to choking coils D_2'' , D_3'' , D_1'' , whereby the coils of each pair D_1' , D_1'' , D_2' , D_2'' and D_3' , D_3'' are arranged in such a mutual inductive relation as to compensate the differences in current. It is obvious that instead of the three microphones illustrated in Fig. 2, any 70 number of microphones may be effectively connected in parallel in an analogous manner.

In lieu of bringing the choking coils into direct mutual inductive relation in the manner described, the arrangement illustrated in Fig. 3 may be selected. Here the primary coils D_1 , D_2 , D_3 influence inductively secondary coils d_1 , d_2 , d_3 respectively which are so connected with each other (preferably in 80 series to form a secondary circuit) that at a uniform inductive action of coils D_1 , D_2 , D_3 upon said secondary circuit, a current is generated which will neutralize the self-induction of coils D_1 , D_2 , D_3 . Thus only the 85 above mentioned uneven operation of the microphones causes the generation of a compensating current which equalizes said irregularities. The connection illustrated in Fig. 3 has the advantage that the microphone circuits may be laid out independently 90 of each other, while the coupling is effected through the compensating circuit.

I claim:

1. In a device of the character described, 95 a transmitting station comprising a pair of microphones connected in parallel, and mutually inductive current equalizing choking coils connected in series with said microphones and located at the transmitting station.

2. In a device of the character described, 100 a transmitting station comprising a plurality of microphones connected in parallel, and mutually inductive choking coils connected in series with said microphones, the mutual inductive interrelation between said coils being such that with currents of equal strengths passing the microphones, the magnetizing effects of said currents are neutralized, while with currents of unequal 105 strengths passing the microphones, an in-

ductive resistance is offered to the compensating currents flowing between the microphones.

3. In a device of the character described, 5 a transmitting station comprising a plurality of microphones connected in parallel, primary coils connected in series with said microphones, and secondary coils connected to form a secondary circuit, the mutual in-
ductive interrelation between the several 10 coils being such that with currents of equal

strengths passing the primary coils, a current is generated in the secondary circuit that neutralizes the self-induction of the primary coils, while with currents of unequal strengths passing the primary coils, an inductive resistance is offered to the current flowing in the secondary circuit. 15
